UNITED STATES PATENT OFFICE.

LEWIS TANNING AND WILLIAM J. RYAN, OF NEW YORK, N. Y.

BOAT-HANDLING DEVICE.

No. 903,025.

Specification of Letters Patent.

Patented Nov. 3, 1908.

Application filed April 10, 1908. Serial No. 426,215.

To all whom it may concern:

Be it known that we, LEWIS TANNING, a resident of the city of New York, borough of Brooklyn, in the county of Kings and State 5 of New York, and WILLIAM J. RYAN, a resident of the city of New York, borough of Manhattan, in the county and State of New York, and both citizens of the United States, have invented a new and Improved Boat- 10 Handling Device, of which the following is a full, clear, and exact description.

Our invention relates to boat-handling devices, our more particular purpose being to enable a boat carried on shipboard, to be 15 readily raised from the chocks, normally supporting it, and otherwise made ready for immediate action upon the water.

Reference is to be had to the accompanying drawings, forming a part of this specification, in which similar characters of reference indicate corresponding parts in all 20 the figures, and in which

Figure 1 is a side elevation showing a boat supported upon the chocks, our improved 25 mechanism being in position to enable either or both ends of the boat to be raised slightly from the chocks, the latter being at the same instant lowered; this view further showing the means whereby the gunwales are held securely while the boat is out of use; Fig. 2 30 is a front elevation of the mechanism shown in Fig. 1, this view particularly showing the position occupied by the chocks while supporting the boat, and also showing one of 35 the rollers engaged by the keel and adapted to lift the boat by the partial rotation of a hand-operated lever; Fig. 3 is an enlarged fragmentary section upon the line 3—3 of Fig. 2, looking in the direction of the arrow, 40 this view showing one of the rollers supporting the keel, and further showing a bracket serving as a stop for limiting certain movements of the roller; Fig. 4 is a fragmentary section upon the line 4—4 of Fig. 2, 45 looking in the direction of the arrow, and showing one of the chocks, and also showing the rocking shaft, whereby both chocks are supported; and Fig. 5 is a fragmentary section upon the line 5—5 of Fig. 2, 50 looking in the direction of the arrow, and showing one of the spurs, whereby the gunwale chains are normally held down while the boat is out of action.

The boat is shown at 6, and is provided 55 with gunwales 7 and with a keel 8. Resting upon a surface 9, which may represent

the deck of a vessel, are cross beams 10. Mounted upon each of these cross beams are bearings 11, supporting a rocking shaft 12, having nearly the same length as the beams 60 10. Two arms 13 are secured, one upon each shaft 12, these arms being upon the same side of the boat. At 14 are the chocks, which are mounted upon arms 15, 16, the latter being secured rigidly upon the shafts 12. 65 Mounted upon each shaft 12, is a spur 17, these spurs engaging the lowermost links of chains 18. These chains are provided with turnbuckles 19, whereby they may be adjusted slightly as to length. The upper ends 70 of these chains are provided with gunwale hooks 20, which engage the gunwales 7 of the boat.

Mounted upon the keel 8 of the boat, are brackets 21. Rollers 22, each having substantially the same thickness as these brackets, are mounted upon forks 23, the latter being secured rigidly upon the rocking shafts 12. 75

The operation of our device is as follows: The boat when removed from the water is rested upon the chocks, as indicated in Fig. 2, the arms 13 being brought into vertical position, as shown in Fig. 1. The gunwale hooks 20 are next hooked upon the gunwales, and the levers 13 moved slightly, so as to tighten the chains 18. The turnbuckles 19 are adjusted so as to remove any inequality in the length of the chains. The boat is now unable to move to any perceptible extent in any direction. 80 85 90

Suppose, now, it is desired to get the boat ready for the water. The arms 13 are turned by hand, as indicated by dotted lines in Fig. 1, and the shafts 12 turn slightly 95 and move the spurs 17, thereby slackening the chains 18. The gunwale hooks 20 may now be removed from the boat if desired, or if not, they may be left secured in position, the loose chains being nicely thrown into 100 the boat. The same movement of the shafts causes the forks 23 to turn, thereby slightly lifting the keel 8, and consequently raising the entire boat for an instant only, so as to disengage the spurs from the gunwale 105 chains. A continuation of the same movement disengages the boat entirely and leaves it hanging in the fall, ready to swing out.

It will be noted that when the parts are in their normal positions, as indicated in Fig. 1, the weight of the boat tends to keep 110 the forks 23 slightly inclined toward each

other, so that the rollers 22 engage the brackets 21, serving as limiting stops for the same.

Having thus described our invention, we 5 claim as new and desire to secure by Letters Patent:

1. The combination of a boat provided with a keel and with brackets mounted upon said keel, forks mounted independently of 10 said boat and provided with rollers for engaging said keel and also for engaging said brackets, and means controllable at will for turning said forks.

2. In a boat handling device, the combination of a rock shaft, chocks controllable 15 thereby for supporting a boat, and mechanism connected with said rock shaft for raising the boat as the chocks are lowered.

3. In a boat handling device, the combination of a rock shaft, chocks mounted rigidly thereupon and adapted to turn radially therewith, a fork mounted rigidly upon 20 said rock shaft and provided with a portion for engaging the keel of a boat, said fork and said chocks all set at different angles 25 relatively to said rock shaft, so that partial rotation of said rock shaft may lower said chocks and raise the upper end of said fork.

In testimony whereof we have signed our names to this specification in the presence 30 of two subscribing witnesses.

LEWIS TANNING.
WILLIAM J. RYAN.
